ATTORNEY.

UNITED STATES PATENT OFFICE.

JOHN J. CAIN, OF BAYONNE, NEW JERSEY.

KNOCKDOWN SHIPPING CONTAINER.

Application filed January 23, 1923. Serial No. 614,396.

To all whom it may concern:

Be it known that I, JOHN J. CAIN, a citizen of the United States, residing at Bayonne, county of Hudson, State of New Jersey, have invented certain new and useful Improvements in Knockdown Shipping Containers, of which the following is a specification.

The object of this invention is to provide 10 a shipping container of three pieces of sheet metal only, in barrel or other desired form, adapted to be shipped to the place of use in knockdown condition, the form of said parts being such as to admit of close nesting or 15 packing in bundles to reduce shipping expenses to a minimum.

Another object is to so form the three parts that they may be quickly assembled ready to receive articles of hardware or other 20 merchandise to be shipped, securely enclosed and fully protected at all times and under all transportation conditions.

A salient feature of the invention is to 25 avoid the use of extraneous or loose securing devices in the assemblage of the sheet metal containers; this is provided for by forming one or more of the three parts with tongues or other fastening means, preferably integral therewith, adapted to be quickly 30 and easily set to lock the meeting edges of and the three parts of the container securely together, thus, besides reducing cost of manufacture, greatly facilitating putting the parts together.

Embodiments of the invention are illustrated 35 in the accompanying drawings, in which:

Fig. 1, shows in elevation, a cylindrical sheet metal barrel made according to this 40 invention, with parts broken away to more clearly show details of construction.

Fig. 2, is an end view of the barrel showing the parts duly assembled.

Fig. 3, represents a sheet metal blank, 45 adapted to form the body of the barrel, with the locking or fastening devices integral therewith, ready to be rolled or otherwise shaped into cylindrical form.

Fig. 4, is a sectional view, on an enlarged 50 scale, taken on the line 4, 4, Fig. 2.

Fig. 5, is an enlarged sectional view taken on the line 5, 5, Figs. 1 and 2.

Fig. 6, is a sectional view similar to Fig. 5, showing a modification in the fastening 55 tongues.

Fig. 7, is a view similar to Fig. 4, showing a modification in the fastening tongues.

Fig. 8, is a fragmentary section taken on the line 8, 8, Fig. 1.

Fig. 9, is a section taken on the line 9, 9, 60 Fig. 1.

Fig. 10^a, is a fragmentary section, similar to Fig. 4, showing a modification in the formation of the head holding tongues.

Fig. 11^a, is a face view of the same, and: 65

Fig. 12^a, is a view similar to Fig. 10^a, showing another modification.

From the foregoing, elucidated by the following description of the drawings, it is evident that the principles of construction 70 of the invention may be applied to forms of containers other than cylindrical barrels shown, as for instance rectangular boxes, polygonal sided receptacles, &c.

Referring to Fig. 3, the rectangular blank 75 of sheet metal 10 is of a size to form the body of a barrel, its length being sufficient to provide overlapping meeting edges 11 and 12, at the vertical seam, see Fig. 1; one of said edges, as 11, has tongues or fastening 80 lugs 13, cut, stamped or otherwise formed in it, which are bent up after the blank sheet has been cylindrically formed, as by a rolling process, the other edge is provided with slots 14, which are caused to embrace 13, 85 when in raised or right angular position, as shown at 15, Fig. 1; the other lugs 13 in Fig. 1 being shown flattened down against the edge lap 12 of the body, also clearly shown in Fig. 8. To further insure good locking 90 connection at this seat it is proposed, when the slots are made to force up one of their sides into pocket form, as at 16, leaving openings sufficiently wide for the free entrance of the lugs 13 therethrough, as shown 95 at the central part of Fig. 1 the resulting ridges being preferably forced down tightly against the bends of the lugs 13, see the lower connection in Fig. 1, also indicated at Fig. 8, thus closing the slots to make such 100 parts of the container water tight.

To add rigidity to the body 10, beads 17 may be rolled longitudinally in it when it is cylindrically formed, and short coacting beads 18 may be formed in the edges 11 and 12 to assist in holding the body in rolled condition. These coacting beads may be made, and preferably, when the lugs and slots are formed.

The longitudinal edges of the blank 10 110

may in some cases be provided with a suitable number of fastening tongues 19, formed by cutting away the sheet metal between them, as shown in Fig. 3. These tongues 5 are bent or folded down against the body 10, preferably before or when the blank is rolled into shape, as seen at two places in Fig. 3, and at the lower right hand corner of Fig. 1.

10 To further assist in holding the overlapping edges together notches 20 are cut in the longitudinal edges at one end of the blank, as edge 12, and lips 21, are formed at the other end of the blank by nicks 22; these 15 lips are bent over the notches, as shown in Fig. 1 and the sectional view Fig. 5.

The heads 23 have peripheral flanges formed at right angles to their flat body portions by reverse cupping or folding of 20 the metal, providing annular spaces or channels between the inner and outer walls 24 and 25 of the flanges. These channels seat over the end edges of the body 10 when the 25 parts are assembled; the heads being then held securely in place by bending the tongues 19, whether formed as in Figs. 4, 6, 7, 10^a or 12^a, against the outer walls 25, over the bends of and inwardly against the inner walls 24 of the channeled flanges, as 30 clearly shown in the detail sectional views of the drawings.

This double wall construction of the flanges of the heads provides the barrel with strong rigid chimes capable of resisting 35 rough usage.

To facilitate applying the heads to the bodies the outer walls 25 of the flanges are of less depth than the inner walls 24, which extend from the flat portions 23 by well defined rounded corners, thus permitting the 40 inner flanges of the heads to be easily slipped into the body and the hollow or channeled flanges set over the edges of the same.

45 The flat portions of the heads may be stiffened by beads or ridges 26.

In some cases the fastening tongues may be formed and bent over the flanges 24-25 of the heads as shown in Fig. 7, by cutting 50 the tongues down in the edges of the blank 10, a distance equal to the depth of the outer walls 25 of the head flanges, said tongues being bent outwardly and against the outer and inner walls of the flanges as before described. The blank 10 will thereby be reduced in width about equal to twice the 55 depth of the flanges of the heads, and to that extent make a saving of the metal used in the body portions.

60 The metal cut away from the lips 21 may be left thereon and utilized to afford fastenings for holding the heads on the body, by bending this addition to the lips around the flanges, as shown at Fig. 6.

65 Certain articles and merchandise require

that the containers in which they are placed be adequately ventilated. This may be provided for, in containers made under this invention, by cutting the fastening pieces from the body 10, as tongues 27, below the chime line, leaving them connected to the body, see Figs. 10^a, 11^a. These tongues are then bent outwardly and folded around the walls 25 and 24 of the flanges, as before described; this leaves ventilating openings 28 at both 75 ends of the barrel. The blanks will by this method of construction be reduced to minimum width. This minimizing of the blanks may also be accomplished by using strips 80 of metal to act as tongues, applied to and secured to the end edges of the body in any suitable manner, as for instance by making slots 30, at the chime line, through which the strips are passed with their inner ends bent up to lie against the inside of the 85 chime and folded over the edges, as shown in Fig. 12^a; the part of the tongues 29 extending outside the body is folded around the double wall chime, as before set forth.

In shipping the parts knocked down the 90 body portions will be in rolled form with their vertical edges free, and they have sufficient resiliency to permit a number of them being placed within one another; the heads 23 will nest closely together as the annular 95 spaces of the flanges are somewhat flaring.

It will be observed that the end edges or chimes of the container consist of three pieces of sheet metal, and are consequently very strong; the heads may be secured to 100 the body portions by indenting the compound chimes, which may be done by a rolling process or by means of special tools; but the use of tongues or lugs of this invention is thought preferable as fastening 105 means for knock-down containers from a manufacturing viewpoint and for the reason that the parts may be quickly and easily assembled and the merchandise enclosed by unskilled labor.

110 I claim:

1. A knock-down shipping container, consisting of a body portion and two head pieces having peripheral upturned flanges 115 reversely folded to form annular channels, adapted to receive the ends of the body when set up ready for use and tongues at the ends of the body adapted to fold against the outer side wall over the upper part of and downwardly against the inner wall of the 120 flanges of the heads to secure them to the body.

2. A container, comprising a body portion 125 of sheet metal, rolled or formed into shape and having at its meeting edges coating fastening devices integral therewith, a head for each end of the body having a peripheral turned up flange reversely folded to form an annular channel into which an end 130 of the body is seated and tongues integral

with the body adapted to be folded over the flanges to hold the heads on the body.

3. A container, comprising a body portion of sheet metal, rolled or formed into shape and having at its meeting edges coacting fastening devices integral therewith, a head for each end of the body having a peripheral turned up flange reversely folded to form an annular channel into which an end 10 of the body is seated and tongues at the end edges of the body adapted to be folded over the up turned flanges and secure the heads to the ends of the body.

4. A container comprising a body portion 15 of sheet metal rolled or formed into shape with its meeting edges overlapping, lugs formed in one of the laps, coacting slots made in the other lap by slits cut therein with one of the sides pressed into ridge 20 form, said lugs passing through the slots and folded down against the slotted lap and the ridges pressed down and against the bends of the lugs to close the gaps of the slots, heads having peripheral flanges adapted 25 to seat in the ends of the body and tongues integral with the body adapted to fold over the flanges of the heads to securely hold the parts together.

5. A container comprising a body portion 30 of a single piece of sheet metal rolled or formed into shape and having at its meeting edges coacting fastening devices integral therewith, a head for each end of the body having a peripheral turned up flange 35 reversely folded to form an annular channel into which an end of the body is seated, the outer wall of the channel being of less depth than the inner wall to facilitate applying the heads to the body and tongues at

the end edges of the body adapted to fold 40 over the up-turned flanges of the heads.

6. A container, comprising a body portion of sheet metal rolled or formed into shape with its meeting edges overlapping, notches formed in the ends of one of the overlapping edges and lips formed at the ends of the other overlapping edge by slits made in the end edges of the body, said lips being folded in and over the notches, lugs formed in one of the laps, coacting slots in the other 50 lap, ridges at one side of the slots formed by said sides being pressed outwardly, said ridges being pressed down against the bends of the lugs to close the slots after the lugs are passed through the slots and folded against the face of the slotted lap, heads having peripheral up-turned flanges adapted to seat in the ends of the body and tongues at the end edges of the body folded over the 55 flanges of the heads.

7. A container comprising a body portion of a single piece of sheet metal rolled or formed into shape and having at its meeting edges coacting fastening devices integral therewith, a head for each end of the body 60 having a peripheral turned up flange reversely folded to form an annular channel into which one end of the body is seated, tongues formed integral with and at the 65 end edges of the body, initially folded down against the body, and, with the channelled flanges of the heads seated over the ends of the body, bent up along the outer wall around the connecting bends and down 70 against the inner walls of the flanges.

Signed at New York, county and State of New York, this 19th day of January, 1923.

JOHN J. CAIN.
